CLAIM

The ornamental design for a fiber optic closure with surface ornamentation, as shown and described.

DESCRIPTION

FIG. 1 is a front perspective view of a fiber optic closure with surface ornamentation showing our new design;

FIG. 2 is a left view thereof;

FIG. 3 is a right view thereof;

FIG. 4 is a front view thereof;

FIG. 5 is a rear view thereof;

FIG. 6 is a top view thereof; and,

FIG. 7 is a bottom view thereof.

The broken lines in the drawings are included for the purpose of illustrating environmental structure and form no part of the claimed design. In FIGS. 1 and 6, the shading indicates color contrast.
